United States Patent [19]

Swisher, Jr.

US00D323511S

[11] Patent Number: Des. 323,511

[45] Date of Patent: ** Jan. 28, 1992

[54] COMBINED COLD MIX RECLAMATION AND SOIL STABILIZATION MACHINE

[76] Inventor: George W. Swisher, Jr., 1500 Dorchester Dr., Oklahoma City, Okla. 73120

[**] Term: 14 Years

[21] Appl. No.: 452,314

[22] Filed: Dec. 18, 1989

[52] U.S. Cl. D15/23

[57] CLAIM

The ornamental design for a combined cold-mix reclamation and soil stabilization machine, as shown and described.

DESCRIPTION

FIG. 1 is a right side elevational view of a combined cold-mix reclamation and soil stabilization machine, showing my new design, the left side being a mirror image thereof;

FIG. 2 is a top plan view thereof;

FIG. 3 is a front elevational view thereof; and

FIG. 4 is a rear elevational view thereof.
